UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

RAILWAY CAR.

Application filed February 8, 1923. Serial No. 617,662.

To all whom it may concern:

Be it known that I, THOMAS ELLIOTT, a citizen of the United States, residing at Cincinnati, in the county of Hamilton and State of Ohio, have invented certain new and useful Improvements in Railway Cars, of which the following is a specification, reference being had therein to the accompanying drawing.

10 This invention relates to railway cars, more particularly the kind used on interurban and steam railways.

The special feature to which my invention is directed is the provision of a structure in 15 the nature of a vestibule which comprises an enclosure independent of the structure of the cars and which is adapted to be mounted on the platforms of adjacent cars to form a safe housing through which passengers 20 may pass in going from one car to the other.

This vestibule structure also affords protection to the passengers in the case of derailment or accident at the time they are 25 passing from one platform to the other because it is in the nature of a separate unit which forms a complete closure around the passengers, save only for its doorways.

Another feature of my invention is that 30 of combining such a vestibule unit with its passenger enclosing features with two articulated railway cars whose adjacent ends are mounted upon the same truck, so that I produce a novel and highly useful combination of a vestibule enclosing unit, articulated cars and a common truck for both cars.

A further feature is the provision of connections between my vestibule unit and the bolster of the truck, so that as the bolster 40 changes position on curves in the tracks the vestibule will also correspondingly change position to keep itself in substantially the same relation with the car platforms, and which themselves likewise change position.

45 under these conditions. In this way I have perfect flexibility or relative movability between the vestibule unit and the cars and this movability is controlled by the movements of the truck bolster.

50 These several objects are carried into practical effect by the structure illustrated in the accompanying drawings which represent the preferred form of embodiment of my invention.

In the drawings, Figure 1 is a side elevation of two railway cars, their truck and my vestibule unit.

Figure 2 is a plan view of the same with parts of the car structure and of the vestibule in horizontal position.

Figure 3 is an enlarged detail sectional view taken on the line 3—3 of Figure 1, showing the vestibule unit on the car platforms, and the spring pressed guards.

Figure 4 is an enlarged vertical sectional view of a part of the car roof structure, showing a spring pressed weather strip and the top of the vestibule unit.

Figure 5 is a vertical sectional view on an enlarged scale of the upper part of the vestibule unit showing most particularly its top or roof construction.

Figure 6 is a longitudinal vertical sectional view of a portion of the two adjacent cars, the central bearings therefor, and the truck bolster.

Figure 7 is also a vertical sectional view, in a transverse direction, showing the central bearing for one car, the bolster and the interlocking rods between the vestibule unit and the bolster.

Viewing Figures 1 and 2, the numerals 1 and 2 generally designate two railway cars whose adjacent ends are supported by a single truck common to both cars at this point. There is nothing peculiar about the car structure or the truck, in so far as concerns my present invention, further than to say that the two cars are articulated through their pivotal support and connection with the bolster of the one truck. The platforms of the cars indicated 3 and 4 in Figure 2, with their end housings 5 and 6 approach one another near the central line but thence diverge one from the other to permit of the swinging of the cars in the different relative positions in going around the curves.

The support of both the cars by a single truck is best illustrated in detail in Figure 6 where it will be seen that the under beam 7 with its transverse angle bar 8 of the car 1 and the under beam 9 with its transverse angle bar 10 of the car 2 are equipped with stout, hollow studs 11 and 12 respectively, which are cylindrical in shape and terminate in spherical ends 13 which fit in the spherical sockets in the bearing plate 14.

carried by the truck beam 15. The studs are positioned one in advance of the other and are capable of rocking fore and aft and laterally, and form practical universal connections with the plate, so as to permit the cars to assume different positions relative to each other and to the truck.

Metal floors 16 are provided for the cars with wood floors 17 overlying them. It 10 will be noted that the metal floors 16 extend out and over the beams 8 and 10, while the wood floors terminate well back from these beams.

The details of the structure so far described do not enter into my invention, but, broadly speaking, articulated cars, that is to say, two cars whose adjacent ends are supported upon a single truck in a pivotal manner, do enter into the combination which 20 forms one part of this invention, to wit, the combination of two articulated cars with a vestibule unit which forms an enclosing structure within which passengers may stand and through which they may pass from car 25 to car.

Referring now to this vestibule unit, it is to be observed that it comprises, generally, a shell formed of walls which constitute an enclosure in the nature of a small room. The 30 preferred form of this vestibule unit is cylindrical as seen by the wall 18 in Figures 2 and 3, while at the bottom is a floor 19 and at the top a roof 20. Sheet steel is the preferred material though the vestibule unit 35 may be constructed of some other material and of some other shape or outline than cylindrical.

The floor 19 rests upon the wood floor 17 of the two adjacent car platforms and over- 40 laps the two platforms so as to bridge the gap between them. There is no positive connection between the vestibule and the platforms. It may be said to float or merely rest upon the platforms.

45 The vestibule, is however, connected to the bolster 15 as best seen in Figure 7. The preferred means of effecting this connection consists of rods 21 which are mounted in clips or bearings 22 in the vestibule and extend down past the ends of the car platforms and enter sockets 23 in the bolster of the truck. The rods have portions 24 which form handles to enable the rods to be manipulated or lifted when it is desired to dis- 55 connect the vestibule from the bolster.

It will now be understood that as the truck turns from side to side in following the direction of the curvatures of the tracks, the vestibule will be likewise turned, and in doing so will oscillate back and forth on the car platforms, though will not otherwise change its relative position to the cars.

The vestibule has doorways indicated at 25 and 26 at the sides of which wood posts

27 are erected about which the metal walls 6 are bent and secured as seen at 28 particu- 70 larly in Figure 3. The position of the posts and therefore of the sides of the doorways is such that when the cars swing to their extreme positions as in going around a curve having say a radius of 35 feet (about the minimum radius) the housings 5 and 6 at the 75 ends of the cars will not pass the door openings, but even under such extreme positions as here assumed, the position nearer to the openings is indicated by the dotted line *aa* in Figure 3.

In order to make a close fit, yet a yielding one, to allow the rocking motions of the cars, I form a pocket 29 in each structure 80 5 and 6 and mount therein guards 30 in the form of strips of wood which are urged against the cylindrical wall of the vestibule by springs such as 31. In this way the 85 guards hug the vestibule but permit of the necessary flexibility in the relation of the vestibule to the cars.

In order to maintain a weathertight fit be- 90 tween the top of the vestibule and the car roofs, over the platforms, I connect to the roofs a pocket structure 32 which is best seen in Figure 4, in which I mount a weather strip 33 urged by a suitable spring 34 against a rubbing board 35 mounted on the roof or top 20 of the vestibule. A rubber or other 95 flexible packing 36 is connected to the weather strip and adapted to lie firmly on the rubbing board to more effectively keep out snow, and rain. The weather strip and the packing rub against the board 35 as the 100 cars move along, but the weatherproof joint is retained. Each car platform roof is so equipped at the point over the vestibule as shown by the dotted lines "b" in Figure 3.

In order to construct a gutter to receive 105 rain and melted snow, the rubbing board 35 is bevelled at its edges 35^a as seen in Figure 5, to leave a gutter 37 between it and the ad- 110 jacent part of the side wall. A drain pipe 38 extends down inside the vestibule and empties below it to discharge the water.

It is, of course, to be understood that the 115 numerous details I have described may be modified to suit different installations of my vestibule unit without departing in any way from my invention.

By now referring back to the introductory statement of the objects and purposes of my invention, its value and utility will be appreciated. It forms, through the office of the vestibule unit, a safe, protecting enclosure through which passengers may pass from one car or car platform to another and which protects them while within the vestibule, be- 120 cause it surrounds them and divides them off from the nearby portions of the car struc- 125 ture.

Again, this vestibule unit maintains a firm

but yielding contact with the platform structures, while it also excludes rain and wind and very largely excludes dust.

Again the connection of the vestibule unit with the truck bolster not only maintains the proper position of the vestibule with respect to the car platforms, which themselves are pivoted to the bolster, but also forms a sort of anchor for the vestibule which prevents it from working away from its mounted position, for while it swings back and forth with the swinging movement of the bolster, yet it always maintains the same general position.

15 I regard myself to be the first to invent a vestibule unit comprising an enclosing structure and combined with adjacent car platforms.

16 I also regard myself as the first to produce a vestibule unit forming an enclosing structure combined with the platform of articulated cars.

20 I further regard myself as the first to provide a vestibule unit comprising an enclosing structure combined with and connected to a railway truck.

25 The utility of this invention has been demonstrated by its manufacturer and introduced into practical use upon various railway lines.

30 Having thus fully described my invention, what I claim as new and desire to secure by Letters Patent is:—

1. The combination with two adjacent cars and a supporting truck common to both cars and to which they are articulated, of a vestibule unit comprising a separate closure adapted to ride on the adjacent platforms of such cars and supported on said 35 truck through the intermediary of said platforms, and having door ways through opposite portions of the side walls.

2. The combination with two adjacent cars each having a projecting platform and a truck common to both cars and to which each platform is articulated, of a vestibule overlapping such platforms, supported thereby and positioned above the point of articulation between the platforms and truck.

3. The combination with two articulated cars of a vestibule unit comprising an enclosure overlapping the adjacent platforms of the cars and having a connection with the truck bolster to cause the vestibule unit to move in unison with the bolster to keep it properly positioned with respect to the cars as they change relative position on curves.

4. The combination with two articulated cars mounted on a truck common to both, of a vestibule unit comprising an enclosure

positioned to partly rest on each platform and devices which connect the vestibule with the bolster for the purpose stated.

5. The combination with two articulated 65 cars mounted on a truck common to both, each car having yieldingly mounted guards, of a vestibule unit comprising an enclosure positioned to partly rest on each platform and to make contact with said guards and means for connecting the vestibule with the bolster of said truck.

6. The combination with two articulated cars mounted on a truck common to both, each car having yielding guards, of a vestibule unit comprising an enclosing structure of cylindrical form adapted to contact with said guards and also adapted to overlap the adjacent platforms of said cars.

7. The combination with two articulated 80 cars mounted on a truck common to both, the adjacent platforms of each car having pockets and vertical guards slidingly mounted therein and each having other pockets with horizontal weather strips slidingly mounted therein and extending transversely, of a vestibule unit comprising an enclosing structure of cylindrical form, the side walls of the vestibule being adapted to contact with the guards and the top of the 85 vestibule to contact with the weather strip.

8. The combination with a car platform roof having a structure provided with a recess and a horizontal weather strip slidingly mounted therein and urged outward by 90 springs, of a vestibule unit comprising a separate structure adapted to be placed on the car platform and having a top adapted to be contacted by said weather strip.

9. The combination with a truck bolster, 100 of a vestibule unit comprising an enclosing structure and means for connecting the bolster with said vestibule to cause the latter to move in substantial unison with the bolster when deflected by the course of the 105 tracks.

10. The combination with a truck bolster, of a vestibule unit mounted above the bolster and means for detachably connecting the bolster and the vestibule, such means being 110 adapted to cause the vestibule to move in substantial unison with the bolster when the bolster moves about its center.

11. The combination with a truck bolster, 115 of a vestibule unit comprising an enclosing structure of cylindrical outline, and adjustable rods operable in the vestibule causing them to connect and disconnect the vestibule with the bolster.

In testimony whereof I affix my signature.

THOMAS ELLIOTT.
